UNITED STATES PATENT OFFICE.

IRA A. JOHNSON, OF GLENDALE, TEXAS.

SLEEPING-SHIRT.

1,072,469.

Specification of Letters Patent.

Patented Sept. 9, 1913.

Application filed February 17, 1913. Serial No. 748,955.

To all whom it may concern:

Be it known that I, IRA A. JOHNSON, a citizen of the United States, residing at Glendale, in the county of Trinity and 5 State of Texas, have invented certain new and useful Improvements in Sleeping-Shirts, of which the following is a specification, reference being had to the accompanying drawings.

10 This invention comprehends certain new and useful improvements in sleeping shirts and relates more particularly to shirts adapted to be worn by infants and having means for engaging the edge of the bed 15 covering and retaining the same in position.

An object of the invention is to provide a device of this character having shoulder flaps covering the clamps engaged with the 20 bed covering to retain the same in position over the infant.

Another object is to provide a device of this character with the shoulder flaps secured at their inner ends to the neck portion 25 of the shirt while their outer ends are removably secured to the outer edge of the shoulder portions of said shirt.

Another object is to generally improve and simplify the construction of devices of 30 this character and increase the efficiency and commercial value of the same.

With the above and other objects in view, this invention consists in the novel features of construction, combination and arrangement of parts as will be hereinafter 35 more fully described, claimed and illustrated in the accompanying drawings, in which—

Figure 1, is a perspective view of the device 40 with the edges of the cover engaged in the clamping members, the cover being broken away and one of the flaps shown in raised position with the clamping members secured therebeneath also swung upwardly. 45 Fig. 2, is a detail perspective view of one of the clamping members.

It will be understood that similar parts 50 will be designated throughout the several views by corresponding reference characters.

It is a well known fact that frequently the cover is caused to work down from around the shoulders of infants during the night and at other times, thus allowing the 55 infant to take cold, and I have therefore

provided a shirt 1 which may be placed upon the infant and I have provided shoulder flaps 2 for the shirt, which flaps are secured at their inner ends to the neck 3 of said shirt and are detachably secured to 60 the outer portions of the shoulders of the shirt, by the buttons 4 carried by the shirt, the shoulder flaps 2 being provided at their outer ends with the button holes 5. It will be understood that the outer ends of the 65 shoulder flaps 2 may be secured in position in any suitable and preferred manner, however, instead of by means of the buttons and button holes, as shown and described in this application. The shoulder flaps 2 serve 70 to protect the shoulders of the infants and keep the same warm, and also to cover and protect the clamping members 6 which will now be described.

I have shown two clamping members beneath each shoulder flap 2 but it will be understood that any preferred number may be employed. Each clamping member 6 is formed preferably of a U-shaped metallic strip 7 bent centrally upon itself to form 80 lower and upper portions extending substantially parallel to one another when the clamp is in closed position, as will be later clearly understood. The free ends of the upper and lower portions are bent at right 85 angles and toward one another and provided with suitable teeth upon their edges, thus forming coöperating gripping jaws 8 which are normally spaced from one another, owing to the resiliency of the material of which 90 the U-shaped member is constructed and the upper jaw 8 is forced toward the lower jaw by means of the cam lever 9 which operates upon the upper face of the upper portion of the U-shaped member 7 and as the oppositely directed laterally extending lugs 10 engage through the openings in the upper ends of the parallel upwardly directed ears 11 which are bent upwardly from the opposite edges of the lower portions of the U- 100 shaped member 7, said ears projecting slightly above the upper portion of the U-shaped member when said upper portion of the U-shaped member is in its normal position. Each clamping member 6 is secured to 105 the shoulder portions of the shirt 1 by means of an elongated ring or link 12 engaged through the central portion of the U-shaped member 7 and is sewed or otherwise secured to the shoulder portion of the shirt, as 110

within the scope of the appended claims shown at 13. The rings 12 are preferably secured beneath the rear edges of the shoulder flaps 2, thus making it possible for the 5 shoulder flaps to completely cover the clamping members, bringing the edge of the bed covering engaged between the jaws 8 of the clamping members 6 beneath the forward edges of the flaps 2, thereby properly covering and protecting the infant.

It will be understood that while I have described this device as being adapted for infants, the same may be readily made of a proper size to be used for retaining cover 15 on older persons and covering and protecting the shoulders of such persons and it will be evident that this device will be especially desirable and useful in hospitals and other places for properly covering and protecting 20 sick or helpless parties.

While I have shown the preferred embodiment of my invention, it will be understood that the parts of the device may be made of any suitable materials and minor changes 25 may be made in the details of construction

without departing from the spirit of my invention.

Having thus described my invention, what I claim is:—

1. A device of the class described comprising a shirt having shoulder flaps, clamping members beneath the shoulder flaps, means for securing the clamping members to the shoulder portion of the shirt, and means for securing the outer ends of the flaps in position.

2. A device of the class described comprising a shirt having shoulder flaps permanently secured to the neck of the shirt at their upper ends, means for removably securing the outer ends of the flaps in position, and cover engaging means positioned beneath the flaps.

In testimony whereof I hereunto affix my signature in the presence of two witnesses. 45

IR A. JOHNSON.
